UNITED STATES PATENT OFFICE

2,357,824

APPARATUS FOR COATING PAPER

Gerald Haywood, Westernport, Md., assignor to
West Virginia Pulp and Paper Company, New
York, N. Y., a corporation of Delaware

Application April 26, 1940, Serial No. 331,691

4 Claims. (Cl. 91—54)

My present invention relates to improved apparatus for coating paper and the like.

It has been proposed to apply coating compositions to paper by using a roll having a multitude of liquid receiving indentations in its surface whereby to deliver to the paper web a more or less measured amount of such composition or "color." In the type of coating apparatus to which the present invention relates, a transfer roll has been used to carry the color delivered by the liquid receiving indentations to the web. The use of a transfer roll in this manner is of advantage inasmuch as it permits the droplets of color deposited by the indented roll the better to coalesce and form a film for application to the web. However, it frequently happens that this effect is not always obtained; sometimes the design of the indented roll is printed on the web, while other times the coating applied is uneven because of the inability to control the character of the surface of the transfer roll prior to its contact with the indented roll.

The object of my present invention is, therefore, to provide an improved coating device which will not only overcome the above mentioned disadvantages, but will have various advantages not possible of realization by the prior art device above described. In carrying out the invention in its preferred form I provide an endless belt which receives a measured quantity of color and transports same to the paper web so as to afford a much greater opportunity for the color to form into a film during the time of transport upon the belt. A further object is to provide an improved arrangement of the belt per se which will facilitate the steady adjustment of the same and permit, moreover, various operations such as cleaning, pre-wetting, etc., to be performed upon it. A still further object is to so mount the belt with respect to the paper web as to provide a clearance between the belt and the web which can be varied and which in addition will permit of the separation of the belt from the web should an obstruction lodge between these parts.

Other objects of my invention to be attained and the advantages thereof will be apparent as the description proceeds.

Reference may now be had to the following detailed description taken with the annexed drawing, in which

Fig. 1 is a diagrammatic view of an illustrative embodiment;

Fig. 2 is an enlarged sectional view showing the surface of the indented roll in contact with the apron.

Fig. 3 is a similar view showing the contact of the apron with the paper to be coated.

In Fig. 1 the web of paper 10 to be coated passes over the backing roll 11 which may be one of a series of drier cylinders, others of which being denoted by 12 and 13. Disposed away from cylinder 11, for example, on the floor level below, is indented roll 16 which is supplied with color by means of fountain roll 17a in a pan 17 in which is provided a supply of color 18. Roll 17a may be driven in the same direction as roll 16 but at a less speed than said roll, and spaced therefrom slightly as shown. If desired, roll 16 may dip directly into the color pan 17, and the roll 17a omitted.

The surface of the indented roll 16 may be formed in any one of a variety of ways, as by knurling, etching, sand or shot blasting, etc. In general the indentations are of a frequency of 20 from 3,600 to 90,000 per square inch and vary in depth from .001 to .006 inch. Desirably a doctor 19 is provided to limit the amount of color carried by the roll substantially to that contained in the indentations, although under certain circumstances the doctor may be omitted. In contact with the surface of roll 16 is endless belt or apron 20, desirably of rubberized fabric of known type having a uniform surface which passes preferably over a plurality of guide pulleys 21, 22, 23, 24, 25, one of which, 24, is displaced laterally of two of the others, i. e., rolls 23 and 25. By this means the belt 20 may be adjusted in tension without altering the distance between pulleys 21 and 22. To this end roll 24 preferably is mounted 35 in a journal block 26 which is slidably disposed upon a support 27. By means of a weight 28, cable 29, pulley 30, the block 26 may be urged to the left, thereby placing the belt under the desired tension. The pulley 22 is preferably mounted 40 upon a lever 31 having suspended from its end a weight 33 and having its pivot at 32 deriving its support from the ground through member 32a only a portion of which is shown. By means of an adjustable stop 34 mounted on a support 35 45 the position of the pulley 22 and the contacting surface of the belt 20 may be accurately adjusted with reference to the web 10. At the same time the arrangement will permit of the pulley 22 yielding against the force of the weight 33 acting 50 through the lever 31, in case an obstruction should lodge in the nip between the belt 20 and the web 10. Driving gears are indicated in the drawing for the cylinders 11, 12, 13 and for rolls 22, 21 and 16, it being desirable that the speed of travel 55 of the web 10 be equal to that of apron 20.

The arrangement of the belt 20 as shown also permits various operations to be performed upon it; thus, pulley 23 may also constitute a cleaning roll having a doctor 37 upon which is sprayed water from a perforated pipe 38. When the belt passes around pulley 24 it may also be given a further cleaning by means of a brush roll 39. After passing beneath the pulley 24 the belt may be moistened by means of a further spray 40 so as to be wet when the roll 16 is reached. Very often the wire side of the web 10 will yield a certain amount of fuzz to the apron 20, which if allowed to accumulate would interfere with the coating operation. However, by means of the spray 38 and the cleaning roll 39 any such accumulation can be effectively prevented. Furthermore, by having the surface of the apron wet when it receives its coating from the indented roll 16, the formation of a smooth film on the apron is facilitated. (Frequently when coating unsized paper by using a transfer roll instead of an apron the roll becomes dry after contact with the web and thereafter acquires and transfers an uneven film of color because of this dry condition.)

It will be noted that the use of a belt in the manner described has a further advantage over a roll for the same purpose in that the roll is at all times subjected to the action of centrifugal force, which may tend to prevent coalescence of the particles, whereas in the case of a belt a straight line travel is provided in which centrifugal force is not acting. Furthermore, by the provision of the travelling belt described it is possible to install coating equipment upon a Fourdrinier machine with a minimum of modification and rearrangement of existing equipment; for example, the fountain roll and color supply may be located in the basement beneath the machine floor where ample room exists which would not be available on the machine floor level. It will also be noted that the large area of the apron, which is at all times covered with a film of color, permits operations to be performed upon the film as may be desired, such as drying, treatment with chemical reagents, etc.

Any coating colors may be employed that would be suitable with the arrangement without using an offset roll instead of a travelling band. In addition, other colors may be used which would be usable with the offset roll only with difficulty due to the greater opportunity afforded by the travel of the band for the deposited color to form a film.

My improved device may be used for coating paper during its manufacture on the Fourdrinier machine or as a separate operation after the paper has left the machine and has been reeled. Furthermore, when coating paper on the Fourdrinier the coating may be applied either at a point where the web contains a substantial quantity of moisture, as for example, immediately following the press rolls, or after the paper is en-

tirely dry, i. e., containing under 10% moisture. Various other changes may be made in the specific embodiment shown.

I claim:

- 5 1. In a device for coating paper with a uniform coating of color, means for feeding a continuous web of said paper, a roll having in its surface a multitude of uniformly disposed liquid receiving indentations, said roll being separated from
- 10 10. said web, means for supplying said roll with color whereby to fill the indentations therein and enable same to deliver a measured amount thereof, and an endless travelling band having a uniform surface disposed in rolling contact with
- 15 15. said roll to receive color carried thereby and to transport the same to said web and there to transfer said color as a film thereto.
- 20 2. In a device for coating paper with a uniform coating of color, means for feeding a continuous web of said paper, an endless travelling band having rolling contact with said web, means for continuously applying a uniform amount of color to a region of said band remote from said web so as to enable said band to
- 25 25. transfer the applied color to said web at such region of contact, a backing cylinder for said web at such region of contact, a pulley around which said band travels at such region of contact, means for adjusting the position of said
- 30 30. roll toward and away from said web, including means for permitting said pulley to separate from said web in case of an obstruction passing between said band and said web, and means for maintaining said band under tension.
- 35 35. 3. In a device for coating paper with a uniform coating of color, means for feeding a continuous web of said paper, a roll having in its surface a multitude of uniformly disposed liquid receiving indentations, said roll being separated
- 40 40. from said web, means for supplying said roll with color whereby to fill the indentations therein and enable same to deliver a measured amount thereof, and an endless travelling band disposed in rolling contact with said roll to receive color
- 45 45. carried thereby and to transport the same to said web and there to transfer said color as a film thereto, and means for wetting the said band prior to the point at which it receives its charge of color.
- 50 50. 4. In a device for coating paper with a uniform coating of color, means for feeding a continuous web of said paper, an endless travelling band having rolling contact with said web, means for continuously applying a uniform amount of
- 55 55. color to a region of said band remote from said web so as to enable said band to transfer the applied color to said web at such region of contact, a tensioning roll for said band, means for cleaning said band after it has discharged its color to the web, and means for pre-wetting same prior to the point at which it receives its charge of color.
- 60 60. 60.

GERALD HAYWOOD.
